UNITED STATES PATENT OFFICE.

GEORGE W. WILMOT, OF HAZLETON, PENNSYLVANIA, ASSIGNOR TO WILMOT ENGINEERING COMPANY, OF HAZLETON, PENNSYLVANIA, A CORPORATION OF PENNSYLVANIA.

ATTACHMENT FOR CHAINS.

Application filed May 22, 1926. Serial No. 110,860.

My invention relates to attachments for chains employed in heavy duty work by means of which flights, buckets or the like may be mounted at intervals upon such chains.

The general object of the invention is to provide a construction comprising a chain and an attachment, the said chain and attachment being provided with a novel construction of means which combine and cooperate to produce a more rugged and strong construction than heretofore has been practical.

It also is an object of the invention to provide novel means whereby additional bearing contacts between the attachments and the chain structure may be obtained.

Another object of the invention is to provide a construction of the character indicated having means whereby the application of the attachment to the chain structure is facilitated.

To these and other ends the invention comprehends the construction and arrangement of parts as hereinafter described in detail, particularly pointed out in the claims and as illustrated in the accompanying drawing forming a part of this specification and in which I have shown one form of a convenient embodiment of the invention. However, it will be understood that the invention is susceptible of embodiment in other forms of construction than that shown and that changes may be made in the details of construction within the scope of the claims without departing from the principle of the said invention.

In the drawing:

Fig. 1 is a view in vertical longitudinal section of a portion of chain upon which is mounted an attachment embodying the invention, the said chain also being provided with means for cooperating with certain parts of the said attachment;

Fig. 2 is a sectional view taken in a plane at right angles to that in which Fig. 1 is taken;

Fig. 3 is a transverse sectional view taken on the line 3—3 of Fig. 1;

Fig. 4 is a transverse sectional view similar to that of Fig. 3, from one of which attachments the bracket is omitted; and

Fig. 5 is a view in inside elevation of one of the attachments.

Upon reference to the drawing it will be

noted that the chain comprises single or solid links 1 and double links comprising side members 2 and 3 and that the said links are connected by pintles 4 in the usual known manner. The single and double links are, as usual, arranged in alternate relation with respect to each other. The solid links are provided respectively with horizontal longitudinally extending slots 5 across which bars or webs 6 extend. The bars are located at about the middle of the said links. In the construction as illustrated the corners of these cross bars are rounded off so that in cross-section the said bars are of oval shape. The attachments heretofore referred to respectively comprise a base portion 10 having inwardly extending flanges or ribs 11 near the base edge thereof. These flanges are each provided with elongated cut-out portions or notches 12 which terminate at one end in adjacent relation to a cross web 13 which extends between the flanges or ribs 11. The ends of the said cut-out portions or notches adjacent the web or cross rib 13 are rounded, and said rounded effect continues along the adjacent edge portion of the rib 13 so as to form a seat 14 for engagement with one rounded corner portion of the cross bar 6. The relationship of the web of an attachment to the cross bar 6 is clearly shown in Fig. 2 of the drawing. The base portions 10 of the attachments are provided with openings 15 through which bolts 16 are adapted to extend for securing the attachments to a solid link of a chain, the said bolts also extending through the slot 5 of the link. Usually, through not always, two attachments, as shown in Figs. 1, 2 and 3, are applied to or mounted on a link. When so applied or mounted on a link the flanges or ribs 11 project into the slot 5 of the solid link of the chain to which they may be applied. When applied to a link the curved seats 14 of the two attachments contact with the rounded corner portions of one edge of a cross bar 6. The base portions of the attachments are provided with tongue-like extensions 21 in alignment with the flanges or ribs 11 and with the holes 15. These extensions are located within the slot of a link of the chain to which the attachments are secured and they are provided with semicircular seats 22 which contact with a pintle 4, as is clearly shown in Figs.

1 and 2 of the drawing. It will be seen, therefore, that each attachment is provided with two bearing portions which contact with portions of the chain structure, which 5 contact portions receive the force transmitted to the attachments from a flight or bucket which may be mounted upon the brackets 23, of usual construction, which form integral parts of the attachments. The flights, 10 buckets, or the like are adapted to be secured to the brackets 23, the latter being provided with widened face-like portions which are adapted for that purpose.

The slots 12 are elongated, as indicated 15 in the drawing, for the purpose of facilitating the application of the attachment to the chain. It will be observed that the tongue-like extending portions 21, when the attachments are applied to the chain, are located underneath the ends of the side members or bars 2 and 3 of a double link which is connected by a pintle 4 to the solid link upon which the attachments are mounted. If the elongated cut-out portions 20 or notches 12 were not provided, the edges of the flanges or ribs 11 would contact with the cross bar 6 and interfere with the insertion of the extensions 21 underneath the adjoining end portions of the side 25 bars 2 and 3.

In the construction as illustrated in Figs. 1 to 3, inclusive, both attachments are provided with brackets 23 upon which flights, buckets, etc., are adapted to be mounted. It 30 may be that in some cases it will be necessary that only one of the attachments mounted upon a chain link need be provided with a bracket. Such a construction or arrangement is illustrated in Fig. 4, in which 35 one only of the attachments includes a bracket 23. For the purpose, however, of securing the said attachment in place upon a link 1 I have provided a cooperating member or element 25 of the same structure as 40 the base portion of the attachment shown in the preceding figures of the drawing. The inner side of the said member 25 is provided with inwardly projecting flanges 45 or ribs 11, identical with the flanges or ribs 50 correspondingly numbered in the preceding figures of the drawing.

By my invention I am enabled to provide 55 a construction in which a plurality of contact surfaces are provided between the attachments and the chain structure for resisting forces which may be imposed upon the said attachments in the use of the same. One of these points of contact is between 60 an intermediate portion of the attachment structure and an integral portion of a link, while another of the said contacts is with an end of the attachment and a pintle of the chain structure, as a result of which the 65 entire force or load imposed upon the attachment is not transmitted directly to an

integral portion of a link. By reason of the arrangement and relationship of the parts as illustrated and as described a structure of great strength and ruggedness is 70 produced.

Having thus described my invention, what I claim and desire to secure by Letters Patent is:

1. In combination, a chain structure comprising single links at intervals having horizontal slots extending therethrough, bars extending across said slots, pintles for connecting the links of the chain, and attachments respectively comprising means upon their inner sides for engaging the said cross bars and also having means adapted to engage pintles which connect one end of the respective links to which the said attachments are connected and one end of the respective adjoining links. 75 80 85

2. An attachment for a heavy duty chain comprising a member having a base portion provided with inwardly extending flanges arranged in parallel relation to each other and in substantial parallel relation to its base edge, the said flanges being provided with elongated notches, one end of each of which terminates in a shoulder, a web extending between the said flanges and having a surface in alinement with and of the same shape as the said shoulders, the said shoulders and the said web being adapted to contact with a portion of a link to which the attachment may be secured, and the said attachment also having means for engaging a pintle in adjoining relation thereto. 90 95 100

3. An attachment adapted to be mounted upon chain links of heavy duty chain, the said attachment comprising a base portion having inwardly extending flanges arranged in spaced and substantially parallel relation to each other, each of the said flanges being provided with an elongated notch, one end of which terminates in a curved shoulder, a web extending between the said flanges, one edge portion of the said web being in alinement with and of the same shape as the said shoulders and constituting with the said shoulders a seat which is adapted to engage a bar extending across a slot in the link of a chain to which the said attachment is adapted to be secured, and the base part of said attachment being provided with an extended portion which is adapted to contact with a pintle for connecting the adjoining link of a chain to the link upon which the said attachment is mounted. 110 115 120

4. In combination, a chain comprising alternate single and double links, the solid links each being provided with slots extending horizontally therethrough and each having a bar extending across said slot, pintles for pivotally connecting the said links together, the said pintles extending through the said links, attachments, two of which are 125 130

adapted to be mounted upon any selected solid link, the said attachments having inwardly extending flanges spaced from each other and extending lengthwise thereof, the 5 said flanges being adapted to be inserted into the said slot and the flanges of the two attachments upon a link facing toward each other and the said flanges being provided with elongated notches, webs extending between the said flanges, one edge of each web being flush with the shoulders terminating one end of each of the notches of a pair of notches, the said shoulders and the said webs adapted to contact with the said cross 15 bar when the said attachments are mounted on a link, and each of the said attachments being provided with extensions which are adapted to engage one of the pintles connecting the solid link upon which the said

attachments are mounted with the adjoining 20 links, and means for securing the said attachments to said solid link.

5. An attachment adapted to be mounted upon a selected link of a heavy duty chain, the said attachment being provided with a 25 contact portion intermediate its ends for contacting with a portion located intermediate the opposite ends of said link, the said portion being integral with and extending transversely of said link, and with a portion 30 at one of its ends for contacting with an element for connecting the said link to adjoining links of the chain structure.

In testimony that I claim the foregoing as my invention, I have hereunto set my 35 hand this 20th day of May, A. D., 1926.

GEORGE W. WILMOT.
